United States Patent Office

Des. 187,549
Patented Mar. 29, 1960

187,549

TROUBLE LAMP OR SIMILAR ARTICLE

David B. Stone, Worcester, Mass., assignor to The O. C. White Co., Worcester, Mass., a corporation of Massachusetts

Application May 5, 1958, Serial No. 50,811

Term of patent 14 years

(Cl. D48—20)

FIG. 1.

FIG. 3

Fig. 1 is a front elevational view of a trouble lamp or similar article showing my new design; and

Fig. 2 is a bottom plan view;

Fig. 3 is a perspective view thereof with the lower portion of the lamp omitted for convenience of illustration.

I claim:

The ornamental design for a trouble lamp or similar article, as shown.
